ATTORNEY.

UNITED STATES PATENT OFFICE

2,361,776

SEWING MACHINE

Frank A. Kucera, Chicago, Ill., assignor to Union Special Machine Company, Chicago, Ill., a corporation of Illinois

Application September 15, 1942, Serial No. 458,353

20 Claims. (Cl. 112—20)

This invention relates to an improved sewing machine construction and more particularly to the construction and mounting of devices used for guiding and uncurling the edges of work as it is delivered to the feeding and stitch-forming means.

Cup-feed machines of the type commonly employed in the formation of the long, back seams in full-fashioned hosiery are ordinarily provided with uncurler blades which are pivotally mounted on the frame and have work clamping portions adapted to be swung, at will, either into or out of the path of feed of the feed-cups. This uncurling means, which may be swung as a unit, in the manner indicated, is usually provided with a thin central plate and a pair of pivoted blades having portions adapted to be urged yieldingly against the opposite sides of the plate to clamp the work against the latter. It is important in this type of construction, particularly when extremely fine materials are to be handled, to provide absolute parallelism between the contacting faces. Due to the manner of manufacture of these devices, as heretofore constructed, considerable precision has been required in the formation of the various parts and a great deal of time and care has been required in their assembly. The assemblers have resorted to careful bending of the blades in order to achieve the final accuracy desired. This has necessitated leaving the work-engaging portions of the blades relatively soft so that their life has been comparatively short, especially when handling nylon fabric, which is quite abrasive.

A primary object of the present invention has been to devise an improved form of uncurler, adapted for use in the manner indicated, which is simple and inexpensive to make and easy to assemble and apply. Toward these ends the improved construction eliminates the necessity of accuracy or precision in the production of the various parts and the careful bending of the blades by skilled workmen. In lieu thereof provision is made for the ready, relative adjustment of the work-engaging portions of the device in two dimensions. Thus, any lack of parallelism between the contacting surfaces may be quickly corrected. An important advantage of the improved construction is that the fabric-engaging faces of the device may be hardened, since this does not interfere with the relative adjustment contemplated and any distortion due to hardening may be readily corrected. This greatly prolongs the useful life of the device.

Other objects, features, and advantages of the

invention will appear from the detailed description of an illustrative form of the same which will now be given in conjunction with the accompanying drawing, in which:

Fig. I is a view in side elevation of the uppermost portion of a cup-feed sewing machine, showing the improved uncurler applied thereto;

Fig. II is an enlarged detail view, in section, along the line II—II of Fig. I, showing a portion of the uncurler, partly in side elevation and partly in vertical section;

Fig. III is a horizontal, sectional view along the line III—III of Fig. II, and

Fig. IV is a bottom view of the uncurler as indicated by the line IV—IV of Fig. II.

For purposes of illustration, the invention has been shown applied to a cup-feed sewing machine of the type disclosed in the Rubel et al. Patent No. 2,043,711, granted June 9, 1936, and to an uncurler having a mounting of the general type disclosed in the patent to Hacklander, No. 2,131,007, granted September 20, 1938. It will be understood, however, that the invention may be applied to uncurlers having other types of mountings and used in connection with other types of machines.

Referring now to the drawing, the machine is provided with a frame 10 having an overhanging portion from which depends a pair of shafts 11 and 12 adapted to be driven intermittently, during operation of the machine, by connections from the main operating shaft, as well known in the art. At the lower ends of these shafts a pair of cooperating feed wheels 13 and 14 is provided, these being adapted to grip the work and advance it step by step in the formation of a seam. The stitching is performed by a reciprocating needle, secured to a reciprocating needle bar 15, and by a pair of loopers mounted for operation in bearing sleeves 16 and 17. For further details as to the construction and operation of these devices, reference may be had to the Rubel et al. patent above-mentioned.

For the purpose of guiding the work and uncurling the edges of the fabric, as they are fed into the bight of the feed-cups 13 and 14, the improved device now to be described is provided. This device, which is indicated generally by the reference character 18 in Fig. I, is secured by a set-screw 19 to a sleeve (not shown) mounted upon a shaft 20 and journaled in a bearing 21 forming part of a bracket secured by a screw 22 to a portion of the overhanging arm of the frame 10. As disclosed in said Hacklander patent, provision may be made in this mounting for retaining the uncurler in a number of different

positions, i. e., in its active, substantially vertical position, with its lower end between the feed-cups 13 and 14 and its rearward edge closely adjacent to the bight of the latter, or in a partly retracted, loading position, or in a fully retracted, inactive position in which it is substantially horizontal. Suitable detents are provided for retaining the uncurler in any of these positions and a release member 23 is provided for releasing the detents, under certain conditions, to permit the uncurler to be swung from one position to another. All of this is described in detail in said Hacklander patent, to which reference may be had for a fuller disclosure.

The uncurler comprises three primary elements including a main support member 24, which is mounted for pivotal movement, in the manner indicated, about the axis of the shaft 20 and carries at its lower end a fixedly secured, thin plate 25 as a downward extension thereof. The other principal elements of the uncurler are blades 26 and 27, which are mounted for pivotal movement on the main support 24 about axes parallel with the plane of the plate 25. These blades are urged by a spring 28 outwardly above their pivots and inwardly below their pivots to carry portions 29 and 30, respectively, yieldingly against the opposite faces of the plate 25. The work to be fed to the cups 13 and 14, and whose edges are to be uncurled, is adapted to be held between the lower ends 29 and 30 of the blades and the cooperating surfaces of the plate 25. It is in the mounting of the blades for pivotal movement, in the manner indicated, and for correct flat surface engagement with the sides of the plate 25, that considerable accuracy has been required heretofore in the construction of the parts and great care has been required to bend them properly in the course of assembly.

To eliminate the necessity of precision in the manufacture of the parts and of expert care in the assembly and bending of the parts, to cause them to function properly, the following provisions are made, in accordance with the present invention: The main support 24 toward its lower end, in the region of the pivots for the blades 26 and 27, is formed with a rearwardly extending lug which is divided into three parts, i. e., a main central part 31 and two side parts 32 and 33. These parts are all integrally connected with the main support 24 but are separated from each other by slots 34 which provide relatively flexible neck portions 35 and 36 at the ends of the slots. The parts 32 and 33 have lateral wings or extensions 32a and 33a, respectively. Each of the parts 32 and 33 is threaded to receive a small, hollow screw or threaded sleeve 37, the inner end of which is adapted to engage the side of the part 31. The outer ends of the screws 37 are slotted to receive a screw-driver so that they may be turned and adjusted as desired. Large headed screws 38 have their shanks extending through the centers of the hollow screws 37 and threaded into a hole 39 extending through the part 31. This construction is such that the part 32, for example, may be forced closer to or further away from the part 31, causing the lateral wing 32a to flex one way or the other about the neck 35. To force the part 32 further away from the part 31, the screw 38 is removed and the hollow screw 37 is turned further into the threaded opening in the part 32. On the other hand, if it is desired to bring the part 32 closer to the part 31, the screw 37 may be backed out slightly and the screw 38 may then be inserted and tightened to cause

flexing of the neck 35 in the desired direction. In the same way, the part 33 may be independently adjusted in relation to the part 31 to cause the wing 33a to flex in one direction or the other about the neck 36.

The blades 26 and 27 are not mounted directly upon pivots secured to the main support 24 or its extensions but are pivotally mounted upon small bushings 40 which have a substantial clearance with respect to the shanks of screw-threaded studs 41, having threaded engagement with the wings 32a and 33a of the support member 24. Bushings 40 have a snug bearing fit within sleeve-like extensions 42 of the blades and are slightly longer than the sleeve-like extensions of the blades. This construction permits a substantial, relative, bodily shifting of each of the bushings 40, together with its associated blade, in relation to the studs 41 and the setting of the parts in adjusted position. By loosening the screw-studs slightly, the bushings may be shifted to any position permitted by the clearance between the latter and the shanks of the studs and, when the proper position has been determined, in the manner to be explained, the heads of the screw-studs may be tightened against the ends of the bushings to hold the parts in proper position.

In the assembly of the uncurler blades 26 and 27 upon the main support 24, the screw-studs 41 are left sufficiently loose to permit relative bodily adjustment of the bushings 40. The lower ends of the blades are permitted to fall against the opposite faces of the plate 25 while the bushings 40 are adjusted in relation to the studs 41 until the lower portion of each blade is in correct vertical alignment with respect to the cooperating surface of the plate. Studs 41 are then tightened until their heads firmly clamp the bushings 40 against the wings 32a and 33a. The vertical alignment of each blade may thus be independently established very quickly. In Figs. II and III an exaggerated clearance is indicated between the heads of the screw-studs 41 and the hub-like extensions of the blades. This clearance is sufficient only to permit clamping of the bushings 40 without interfering with the free pivotal action of the blades.

There still remains the problem of bringing the cooperating surfaces of the blades and plate 25 into proper horizontal alignment. This is readily accomplished by the flexing of the wing extensions 32a and 33a about the necks 35 and 36, respectively, in the manner hereinabove explained. Thus, full surface engagement of the cooperating faces may be brought about very quickly without bending the blades. This enables the hardening of the fabric-engaging portions of the blades as well as the plate 25 so that these will resist, more effectively, the abrasive action of the fabric. This is of particular importance in dealing with nylon fabrics, which have been found to have a more serious abrasive action than silk and rayon fabrics. The life of the uncurler may thus be greatly increased. That part of the main support which is not subject to the continuous rubbing action of the fabrics need not be hardened and may be of a character readily capable of flexing in the manner required.

The upward extensions 43 of the blades 26 and 27 are inclined outwardly away from the support 24, as shown in Fig. I, and provide finger grips by which the blades may be rocked about their pivots to enable the ready introduction and removal of the work. Screw-threaded guide pins 75 44, having a slight taper at their outer ends, are

carried by the opposite faces of the plate 25 and cooperate with holes 45 through the uncurler blades. These pins serve to determine the height of the fabric passing through the uncurler to the feed cups. The tension of the spring 28, which passes through a hole in the support 24 and acts upon the blades 26 and 27 to urge their lower ends yieldingly against the plate 25, may be varied by an adjusting screw 46 carried by the blade 27. A collar or flange at the inner end of this screw, cooperating with the end of the spring 28, may be adjusted, as desired, to vary the tension of the spring.

While an illustrative embodiment of the invention has been described in considerable detail, it will be understood that numerous changes may be made in the construction and arrangement of the various parts without departing from the general principles and scope of the invention. The terms and expressions employed herein have been used as terms of description and not of limitation.

What I claim is:

1. Work guiding means for a sewing machine which comprises a main support member having rigidly connected therewith a plate-like guide element, and a presser blade pivotally mounted on said member and having a surface urged yieldingly against a surface on said element, the pivot for said blade comprising a bearing sleeve and a supporting stud therefor carried by said member and having a substantial clearance within said sleeve to enable relative, lateral adjustment of said sleeve and stud.

2. Work guiding means for a sewing machine which comprises a main support member having rigidly connected therewith a plate-like guide element, and a presser blade pivotally mounted on said member and having a surface urged yieldingly against a surface on said element, the pivot for said blade comprising a bearing sleeve and a supporting stud therefor carried by said member and having a substantial clearance within said sleeve to enable relative, lateral adjustment of said sleeve and stud, said stud being screw-threaded and adapted to clamp said sleeve in adjusted position.

3. Work guiding means for a sewing machine which comprises a main support member having rigidly connected therewith a plate-like guide element, a presser blade pivotally mounted on said member and having a surface urged yieldingly against a surface on said element, the pivot for said blade comprising a bearing sleeve and a supporting stud therefor carried by said member and having a substantial clearance within said sleeve to enable relative, lateral adjustment of said sleeve and stud, and means for varying the angular relation between said stud and said guide element.

4. Work guiding means for a sewing machine which comprises a main support member having rigidly connected therewith a plate-like guide element, a presser blade pivotally mounted on said member and having a surface urged yieldingly against a surface on said element, the pivot for said blade comprising a bearing sleeve and a supporting stud therefor carried by said member and having a substantial clearance within said sleeve to enable relative, lateral adjustment of said sleeve and stud, and screw-threaded means for varying the angular relation between said stud and said guide element.

5. Work guiding means for a sewing machine which comprises a pair of pivotally connected

members having portions intended to be in flat surface engagement, the pivotal connection between said members being adjustable at will to insure full contact between said portions in one dimension, and adjustable means on one of said members for insuring full contact between said portions in a direction at right angles to said one dimension.

6. Work guiding means for a sewing machine which comprises a pair of pivotally connected members having portions intended to be in flat surface engagement, the pivotal connection between said members being adjustable at will to insure full contact between said portions in one dimension, and screw-threaded means adjustable on one of said members for insuring full contact between said portions in a direction at right angles to said one dimension.

7. Work guiding means for a sewing machine which comprises a pair of pivotally connected members having portions intended to be in flat surface engagement, and means for adjusting the pivotal connection between said members to shift the axis thereof both translationally and angularly in relation to said portion of one of said members.

8. Work guiding means for a sewing machine which comprises a pair of pivotally connected members having portions intended to be in flat surface engagement, means for bodily adjusting the pivotal axis of said members with respect to one of said members and retaining the same in adjusted position, and means for adjusting the angular position of said pivotal axis in relation to said portion of said one of said members.

9. Work guiding means for a sewing machine which comprises a pair of members having work engaging portions intended to be in flat surface contact, and means comprising a stud and a sleeve surrounding said stud with substantial clearance therebetween for pivotally connecting said members, said stud having means associated therewith for retaining said sleeve in any adjusted position in relation to said stud permitted by said clearance.

10. Work guiding means for a sewing machine which comprises a pair of members having work engaging portions intended to be in flat surface contact, means comprising a stud and a sleeve surrounding said stud with substantial clearance therebetween for pivotally connecting said members, said stud having means associated therewith for retaining said sleeve in any adjusted position in relation to said stud permitted by said clearance, and means for adjusting the angular relation between said stud and one of said work engaging portions.

11. Work guiding means for a sewing machine which comprises a main support having integral extensions adapted to be readily flexed in relation to the main body thereof, screw-threaded means adjustable to flex said extensions, and a plurality of members each pivotally connected with one of said extensions and having a portion in flat surface engagement with a portion of said main support.

12. Work guiding means for a sewing machine which comprises a main support having integral extensions adapted to be readily flexed in relation to the main body thereof, screw-threaded means adjustable to flex said extensions, a plurality of members each pivotally connected with one of said extensions and having a portion in flat surface engagement with a portion of said main support, and means for adjusting the piv-

otal connection of each of said members with the related extension.

13. Work guiding means for a sewing machine which comprises a main support having an integral extension adapted to be readily flexed in relation to the main body of the support, means carried by said extension providing a pivot, a member mounted on said pivot, said member having a portion intended for flat surface engagement with a portion of said support, and adjustable screw-threaded means for flexing said extension in relation to the main body of the support to improve the surface contact of said portions.

14. Work guiding means for a sewing machine which comprises a main support having an integral extension adapted to be readily flexed in relation to the main body of the support, means carried by said extension providing a pivot, said means being adjustable on said extension to alter the position of the axis of said pivot, a member mounted on said pivot, said member having a portion intended for flat surface engagement with a portion of said support, and adjustable screw-threaded means for flexing said extension in relation to the main body of the support to improve the surface contact of said portions.

15. Work guiding means for a sewing machine which comprises a main support having an integral extension adapted to be readily flexed in relation to the main body of the support, means carried by said extension providing a pivot, a member mounted on said pivot, said member having a portion intended for flat surface engagement with a portion of said support, and means including a pair of adjusting screws acting in opposition to flex said extension in relation to the main body of the support to improve the surface contact of said portions.

16. Work guiding means for a sewing machine which comprises a main support having an integral extension adapted to be readily flexed in relation to the main body of the support, means carried by said extension providing a pivot, a member mounted on said pivot, said member having a portion intended for flat surface engagement with a portion of said support, and means including a hollow screw and a screw extending through the opening thereof adjustable to flex said extension in relation to the main body of the support to improve the surface contact of said portions.

17. In a sewing machine having a frame, a plurality of rotatable feed-cups, work guiding means carried by said frame adapted to engage

the work in advance of said feed-cups, and stitch forming devices arranged to cooperate with said work adjacent the bight of said feed-cups, said work guiding means comprising a pair of pivotally connected members having work engaging portions intended to be in flat surface engagement, and means for adjusting the pivotal connection between said members to shift the axis thereof both bodily and angularly in relation to said portion of one of said members to bring said portions into flat surface contact.

18. In a sewing machine having a frame, a plurality of rotatable feed-cups, work guiding means carried by said frame adapted to engage the work in advance of said feed-cups, and stitch forming devices arranged to cooperate with said work adjacent the bight of said feed-cups, said work guiding means comprising a pair of members having work engaging portions intended to be in flat surface engagement, pivot means on one of said members for pivotally carrying the other, and means for adjusting the axis of said pivot means both bodily and angularly in relation to the work engaging portion of said one of said members.

19. In a sewing machine having a frame, a plurality of rotatable feed-cups, work guiding means carried by said frame adapted to engage the work in advance of said feed-cups and stitch forming devices arranged to cooperate with said work adjacent the bight of said feed-cups, said work guiding means comprising a pair of members having work engaging portions intended to be in flat surface engagement, pivot means on one of said members for pivotally carrying the other, and adjustable screw-threaded means for enabling the shifting of the axis of said pivot means both bodily and angularly in relation to the work engaging portion of said one of said members and for setting said axis in adjusted position.

20. In a sewing machine having a frame, a plurality of rotatable feed-cups, work guiding means carried by said frame adapted to engage the work in advance of said feed-cups, and stitch forming devices arranged to cooperate with said work adjacent the bight of said feed-cups, said work guiding means comprising a support pivotally mounted on said frame, a plurality of members having portions spring urged into full surface contact with surfaces on said support, pivot means on said support on which said members are mounted, and settable means for varying the position of the axes of said pivot means in relation to said support both bodily and angularly.

FRANK A. KUCERA.
